AUTOMATIC SWITCH.

1,405,338.

Specification of Letters Patent. Patented Jan. 31, 1922.

Application filed April 20, 1912. Serial No. 692,120.

(GRANTED UNDER THE PROVISIONS OF THE ACT OF MARCH 3, 1921, 41 STAT. L., 1313.)

To all whom it may concern:

Be it known that I, LUDWIG SCHÖN, residing at Essen-on-the-Ruhr, Germany, a subject of the Emperor of Germany, have 5 invented a certain new and useful Improvement in Automatic Switches, of which the following is a specification.

The present invention relates to such automatic switches for alternately opening and 10 closing an electric circuit, which are provided with a device for changing the ratio between the duration of the closing and opening. The object of the invention is to provide a switch of this kind and of very simple 15 construction, wherein not only this ratio can be changed within wide limits, and in a steady and very accurate manner, but also the arising of injurious break sparks is excluded.

20 The accompanying drawing shows in—

Fig. 1 a side view, partly in section of one embodiment of this invention with a diagrammatic representation of a connection for a dynamo, wherein the tension is known 25 manner is regulated by changing the relation of duration of the closing and opening:

Fig. 2, a section along line 2—2 of Fig 1, seen from the left;

30 Fig. 3, a diagrammatic sketch corresponding to Fig. 2 illustrating the manner of operation of the device in accordance with Figs. 1 and 2.

The field winding A of the dynamo B is 35 connected to the two main lines +S and —S of a network of continuous current by means of conductors C and C¹. The device constituting the present invention for changing the opening and closing of the electric

40 circuit, is inserted in conductor C. This device consists principally of a cylindrical rotor D, which is rigidly mounted on a shaft H, running in bearings G, G¹, G²; and of two sliding brushes E, E¹ resting on the 45 rotor D, which brushes E and E¹, see Fig. 1, are displaced axially relative to each other. One of these brushes E, is rigidly connected to the bearing G¹ by means of an arm g³; whilst the other brush E¹ is seated on a revolute arm g⁴ arranged on the bearing G; so that the latter brush 50 may be set at any desirable angle relative to the brush E. That part of the jacket

of the rotor D which consists of non-conducting material is provided around its 55 whole circumference with lamellæ d⁵, some of which are connected by an adjustable short circuit member d⁶. This short circuit member can be adjusted circumferentially on the rotor D by any suitable means such as screws or the like. The two brushes E and E¹ are to be dimensioned in the circumferential direction so that each brush 60 in every angular position of the rotor D touches at least one of the lamella. An 65 electric motor F serves to drive the rotor D. The rotor F¹ of the former is carried by the shaft H.

For the sake of simplicity it will be supposed that the brushes E and E¹ only touch 70 the rotor D with a thin edge, see Fig. 3, which illustrates the operation of the described device; and the lamellæ d⁵ short-circuited by the member d⁶ are substituted by a single contact piece d⁴, the central 75 angle α of which is equal to the central angle of the member d⁶. This supposition is admissible, because, as is mentioned above, each brush always touches at least one of the lamellæ, and the short-circuited lamellæ may be considered as a single contact piece as regards the contact with the 80 brushes. Should the adjustable brush E¹ be set in the position indicated by dot and dash lines, wherein it is turned as regards 85 the brush E an angle φ , the circuit can then be closed only during that instant that corresponds to the turning angle $\alpha - \varphi$, which is easily understood from Fig. 3, as by the end of this time the brush E will be out 90 of reach of the sliding contact d⁴. The value

$$\frac{\alpha - \varphi}{360^\circ - (\alpha - \varphi)}$$

95

will then express the relation between the duration of the closing and opening for a complete revolution of the rotor D. This value, as it is easy to prove does only hold good for the case illustrated in Fig. 3; 100 wherein the brush E¹ is displaced an angle φ in the direction of the arrow α relative to the brush E; but also for a displacement in the opposite direction of the arrow.

From the above mentioned reference it 105 follows that said ratio will be equal to 0

for an angular distance of $\varphi=\alpha$ and will assume its maximal value

$$5 \quad \frac{\alpha}{360^\circ - \alpha}$$

for an angular distance of $\varphi=0$. It will also be evident, that within these limits the ratio of the displacement of the brush E^1 can be changed in a steady and very accurate 10 manner.

If the contact between the brushes E and E^1 and the rotor D does not take place, as has been supposed in Fig. 3, with a thin edge, but instead with a broad surface, see 15 Fig. 2, which in reality is the case, the angle corresponding to the central angle of the contact surface of the brushes must be considered enlarged, in order that the last derived equation shall hold good. In the 20 same way as above described for the case of a single contact piece, the device shown in Figs. 1 and 2 works in the case of a rotor with lamellæ d^6 , some of which are short-circuited by the member d^6 . As the 25 lamellæ which are not connected by means of the short circuit member d^6 can never produce a connection between the two brushes as long as the angular displacement between the brushes E and E^1 (see Fig. 2) 30 is not equal to or almost equal to zero, the opening and closing of the circuit will evidently follow in the same length of time as in the arrangement according to Fig. 3, with the exception of when the brushes 35 have an angular displacement of zero as just mentioned.

The construction of the rotor in the shape of a collector provides the advantage, that the sparks at the break are sooner extinguished by jumping over to the nearest lamellæ, than what is the case in known 40

devices. The circumferential adjustability of the short circuit member d^6 makes it possible to proportionately divide the resulting wear all over the lamellæ of the 45 rotor D notwithstanding the influence of the sparks.

Claims.

1. In an automatic switch for alternately opening and closing an electric circuit, a 50 device for changing the ratio between the duration of the closing and opening, comprising a rotor, two brushes resting on said rotor, one of said brushes being circumferentially adjustable as regards the 55 other brush, for the purpose of changing the ratio between the duration of the closing and opening, said rotor being constructed as a laminated collector, and having a short circuit member connecting some of the 60 lamellæ of said rotor.

2. In an automatic switch for alternately opening and closing an electric circuit, a device for changing the ratio between the duration of the closing and opening, comprising a rotor, two brushes resting on said 65 rotor, one of said brushes being circumferentially adjustable as regards the other brush, for the purpose of changing the ratio between the duration of the closing and 70 opening, said rotor being constructed as a laminated collector, and having a short circuit member connecting some of the lamellæ of said rotor, said short circuit member being circumferentially adjustable. 75

The foregoing specification signed at Barmen, Germany this 30th day of March, 1912.
